Primary Examiner — Cynthia Ramirez*Assistant Examiner* — Gino Colan*(74) Attorney, Agent, or Firm* — Lorenz & Kopf, LLP(57) **CLAIM**

The ornamental design for a control grip, as shown and described.

DESCRIPTION

FIG. 1 is a top, rear, right perspective view of a control grip showing our new design;

FIG. 2 is a top, rear, left perspective view thereof;

FIG. 3 is a right side elevational view thereof;

FIG. 4 is a left side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines shown in the Figures are for the purpose of illustrating environment and form no part of the claimed design.

The nature of this product is a control grip or portion thereof, such as for use by an operator during operation of a work vehicle for operator stabilization and/or machine control purposes.
